IGNITION SYSTEM.

1,287,705.

Specification of Letters Patent. Patented Dec. 17, 1918.

Application filed April 26, 1916. Serial No. 93,605.

To all whom it may concern:

Be it known that I, GEORGE L. LANG, a citizen of the United States, residing at Newark, in the county of Essex and State 5 of New Jersey, have invented certain new and useful Improvements in Ignition Systems, of which the following is a specification.

My invention relates to improvements in 10 ignition systems for gas engines in which the source of current supply is a battery or a direct current generator ordinarily used for charging the same.

One of the objects of my invention is to 15 provide means for automatically opening the ignition circuit should the engine stop in such a position as to leave the ignition circuit closed, which would cause the battery to discharge through the primary of the induction coil with the possibility of burning the same up. I attain said object by means 20 of a thermostatic device, preferably constructed of two dissimilar expansion elements having different coefficients of expansion, around which, in my preferred form, 25 is wound several turns of wire, usually of a special kind that is included in the primary circuit of the induction coil, taking in the interrupter or timer contact operated 30 by the engine. When the engine is in operation the amount of current flowing through the thermostatic coil is not sufficient to cause the coil to heat enough to act on the expansion elements, but should the engine be 35 stopped with the timer contact closed then the increased flow of current, which results due to only the ohmic resistance of the primary circuit, is sufficient to heat the expansion elements, causing the same to expand 40 in one direction thus closing a pair of contacts controlling an electro-magnetic device, which in turn operates through the necessary members, also manually controlled, to open the circuit of the primary of the coil, 45 should the operator forget to do this himself.

Another object of my invention is to provide switching mechanism for my ignition system which is simple in form and easy to 50 manufacture.

Other and further objects of my invention will be apparent to one skilled in the art, after a study of this specification taken in connection with the drawing attached 55 thereto.

In the drawing, Figure 1 illustrates a side elevation of my improved switching mechanism with the cover removed. Fig. 2 is a top plan view of Fig. 1 with the detent armature removed from the electro-magnetic 60 device. Fig. 3 is a sectional view of the cover adapted to fit over the switch shown in Fig. 1. Fig. 4 is a diagrammatic arrangement of a preferred form of my ignition system. 65

Referring particularly to the details shown in the various views wherein like numbers refer to corresponding parts, 1 is a base of insulating material upon which is mounted the member 2 having upright legs 3 and 4. 70 Pivotaly mounted to leg 4 is a detent armature 5 adapted to be acted on by the electromagnets 6. Attached to the leg 4 is a piece 7 which passes through a slot in the detent 5 and having its end 8 bent over to 75 act as a stop for the said detent 5. Pivotaly mounted to the leg 3 is an L shaped member 9 having a resilient member 10 attached to the member 2 and operating on the member 9 to hold it in the position shown in 80 full lines. A contact 11 is carried by the upper arm of the member 9 and this contact is adapted to co-act with the contact 12 mounted on a spring 13 that is attached to the post 14. Attached to the base 1 is 85 a contact post 15 carrying a contact 16, also mounted on the base 1 is a supporting bracket 17 to which is rigidly attached two expansion strips 18 and 19 of dissimilar materials having different coefficients of ex- 90 pansion. A contact 20 adapted to coöperate with the contact 16 is attached to the end of these strips. In my preferred form said expansion strips are covered with insulation 21 of a suitable character, such as mica, 95 and around the insulation is wound a coil 22 which is preferably a special resistance wire. The two strips 18 and 19 are capable of being put under more or less tension as regards their ability to move toward the 100 contact 16 by an adjusting screw 23. One end of the coil 22 is connected to the binding post 14 and the other end to the terminal post 24. The two coils 6 are connected in series, one terminal being connected to terminal post 25 and the other to the bracket 17. The cover 26 is designed to fit over the base 1 being attached thereto in any suitable manner, and has a flange 27 for mounting the switch on a mounting plate such as the 110

cowl board of an automobile. The cover 26 is provided with two push buttons 28 and 29. When the cover 26 is in place on the base 1, the push button 28 having a plunger 31 is in line with the horizontal portion 30 of the member 9, and the push button 29, having a plunger rod 32 is in line with the detent armature 5. (See Fig. 4).

The operation of the switching mechanism and its relation to my ignition system will be clearly understood by the following description of the circuit arrangement shown in Fig. 4. In this figure, 34 is a cam operated in any suitable manner by the engine. The cam 34 co-acts with a lever 35 carrying contact 36 which in turn co-acts with an adjustable contact 37. 38 is an induction coil having a primary winding P and a secondary winding S, one end of which is grounded, and the other connected to the usual distributor for distributing the current from the secondary winding to the various cylinders of the engine. The distributor and sparking devices in the engine 25 are old and well known and will not be further described herein.

B illustrates a battery, or other source of direct current, one terminal of which is shown grounded at G.

30 Suppose it is desired to start the engine equipped with my ignition system. The button 28 is pushed in against the tension of the spring 39 until it hits against the shoulder stop 40. This movement of the push button 28 carries the plunger 31 downward against the leg 30 of the member 9 causing the member 9 to turn about its pivot 41 to the position shown in dotted lines in Fig. 1, thus closing together the contact points 11 and 12. A circuit can now be traced from battery B through the primary P of the induction coil 38 to the member 9, contacts 11 and 12, coil 22 of the thermostatic device, through contacts 37 and 36 of the timer, if 45 in closed position, member 35 to ground G common to battery B. The engine is now cranked in the usual manner and so long as it is kept in operation the circuit through the induction coil 38 will remain as above described. Should it be desired to stop the engine the ignition circuit may be opened by pushing the button 29, against the tension of spring 42 to the shoulder stop 43. This act will carry the plunger 32 against 50 the detent armature 5 pushing the same downward to the position shown in full lines, Fig. 1. As soon as the detent 5 is pushed downward out of the path of movement of member 9, the resilient member 10 will return the member 9 to its normal position shown in full lines in Figs. 1 and 4, thereby opening the primary circuit at the points 11 and 12. It will be noted that both the buttons 28 and 29 are provided with shoulders 55 which engage stops 40 and 43 on the cover

26 so that they cannot be pushed in only a fixed distance, thereby providing a fixed movement to the members 9 and 5 which they respectively engage. Should now for any reason, the engine be stopped without 70 opening the primary of the ignition circuit as above described, and the engine stops so that the contacts 36 and 37 are in engagement, then there will be a relatively heavy current flowing through the primary P of 75 the induction coil 38 which would run battery B down and like enough burn out coil 38. This relatively heavy current passing through the resistance wire coil 22 causes the same to generate heat which acts on the expansion strips 18 and 19 causing them to expand so as to close the contacts 16 and 20. When this happens a circuit is formed from battery B through contacts 16 and 20, metal strips 18 and 19, bracket 17, coil 6, member 85 9, across contacts 11 and 12 through coil 22 and timer contacts 37 and 36 to ground side of battery G. The coils 6 will then be in multiple with the primary P of the coil 38 and the current in both multiple paths will 90 pass through coil 22 which will thus get the benefit of the current passing through electromagnet coils 6, thus making the movement of the thermo-element quicker and more positive than it would be if the current 95 for the electro-magnet did not pass through the thermo-coil. This current passing through the coils 6 will energize the same and pull the detent 5 downward out of the path of movement of member 9, which will 100 return to its normal position, herein before described for the manual operation. As soon as the contacts 11 and 12 are open the thermostatic device returns to its normal position opening the contacts 16 and 20. 105

By my method of circuit connections, I avoid carrying the regular ignition current through the expansion strips themselves, of the thermostatic device. I consider this an advantage as the thermostatic device is not 110 so likely to operate and open the ignition circuit as I have found it does when the ignition current is carried through said strips, when running the engine at very low speed at which time the current through the primary of the induction coil is greatest due to the less number of breaks per second at the timer, and consequently a lower inductance in the primary of the coil; also the thermostatic device returns to its normal position 115 quicker when the expansion strips themselves do not carry current and do not become heated thereby.

Instead of winding the heating coil around the expansion strips, I may arrange it in any 120 satisfactory adjacent place, and it will be understood that various other changes and alterations can be made in the details of my switching mechanism without departing from the spirit and scope of my invention. 130

Having thus described my invention what I claim is:—

1. In an ignition system, the combination of a source of current, an induction coil, an interrupter, a thermostatic device having adjustable expansible elements carrying a contact and a heating coil electrically insulated therefrom, switching means having a manually movable member for closing a contact to switch the first three mentioned elements and the heating coil into a circuit, means for retaining a part of said switching means in operative position when moved thereto, a second circuit normally excluding said expansible elements from the direct flow of current in the first circuit for the purpose described; said second circuit, including the interrupter, heating coil, switch contact, expansible elements and an electromagnet, closed by said contact carried on the expansible element when said interrupter remains closed for an abnormal length of time, whereby said electromagnet acts positively on said retaining means to withdraw the same to allow that part of the switching means controlling the manually operated contact common to both circuits to open the same as described.

2. In an ignition system, the combination of a source of current, an induction coil, an interrupter, an adjustable thermostatic device having an expansible element and a heating coil, a switch having coöperating manually operated members both visual and concealed for switching the first three mentioned elements and the heating coil into fully closed circuit position and resilient means for returning all of the said manually operated members to open circuit position, mechanical means for holding said concealed switch member in its fully closed circuit position, an electromagnet brought into operation by said thermostatic device for acting

directly on said holding means for moving the same from its holding position, whereby 45 the resilient means may act on said concealed manually operated member to open said circuit.

3. In an ignition system, the combination of, a source of current, an induction coil, an interrupter, a thermostatic device having substantially parallel strips of material of different coefficients of expansion and a heating coil wound around said strips but not electrically connected thereto, a switch having a manually operated member for switching the first three mentioned elements and the heating coil into circuit, a detent for holding said manually operated member in operated position, an electro-magnetic means 60 brought into operation through said strips by the action of said coil thereon for withdrawing said detent from the path of movement of said manually operated member when said interrupter remains closed for an 65 abnormal period of time and resilient means acting on said manually operated member to move the same to open circuit position.

4. In an ignition system, the combination of, a source of current, an induction coil, an 70 interrupter, a thermostatic device having a heating coil as one element thereof, a switching device having a movable member for switching said elements into circuit, a self returning push button to act on said movable 75 member, a detent engaging said movable member to hold same in closed position after being acted on by said button and a second self returning push button to act on said detent to remove same from the path of 80 movement of said movable member and resilient means for returning said movable member to open circuit position.

In witness whereof, I affix my signature.

GEORGE L. LANG.
